UNITED STATES PATENT OFFICE.

JULIAN A. HURDLE, OF WASHINGTON, DISTRICT OF COLUMBIA.

IMPROVEMENT IN BOUQUET-HOLDERS.

Specification forming part of Letters Patent No. **174,364**, dated March 7, 1876; application filed February 4, 1876.

To all whom it may concern:

Be it known that I, JULIAN A. HURDLE, of Washington, in the District of Columbia, have invented certain new and useful Improvements in Bouquet-Holders; and I do hereby declare that the following is a full, clear, and exact description thereof, which will enable others skilled in the art to which it appertains to make and use the same, reference being had to the accompanying drawings, and to the letters of reference marked thereon, which form a part of this specification.

The object of my invention is to fasten a bouquet to the lapel of a coat in a manner to prevent the cloth from becoming soiled by the fastener, as I shall fully describe hereafter.

Figure 1 represents the fastener attached to the lapel, and having therein the flowers. Fig. 2 represents the development. Fig. 3 represents the fastener in perspective.

The fastener is circular in form, and has four circular cuts, B' B'' B''' B''', which allows the portions D' D'' D''' D'''' to be bent around the stem of the flowers and holds them firm, while the portion A remains in its original

position. The pin-points C' C'' are to penetrate the cloth, and are to be bent in an opposite direction. This instrument can be made more ornamental than the one represented on the accompanying drawing by having a set in lieu of the portion A in Fig. 3, and extending therefrom the sheet metal having thereon the four cuts that have been previously mentioned and described.

The manner of operation is as follows: Place the stem of the flowers within the concave; then bend the portions marked D' D'' D''' D'''' around them, which holds them firm; then penetrate the cloth with the pin-points C' C'', and bend them in an opposite direction, which produces the results desired.

I claim as my invention—

A bouquet holder or fastener consisting of the curved portion A, wings D' D'' D''' D'''', and pins C' C'', substantially as described.

JULIAN A. HURDLE.
